UNITED STATES PATENT OFFICE.

REUBEN M. PRICE, OF DE LAND, FLORIDA.

KEY MECHANISM FOR WOOD WINDS.

1,317,219.

Specification of Letters Patent. Patented Sept. 30, 1919.

Application filed March 29, 1918. Serial No. 225,438.

To all whom it may concern:

Be it known that I, REUBEN M. PRICE, a citizen of the United States, and a resident of De Land, in the county of Volusia and State of Florida, have invented new and useful Improvements in Key Mechanism for Wood Winds, of which the following is a specification.

This invention relates to musical instruments, particularly that class known as wind reed instruments and has for its objects to so improve the key mechanism of instruments of this class that difficult fingering for certain notes may be avoided and these notes rendered with ease and facility.

A further object is to enhance the value and utility of instruments of this class by simplifying and rendering their manipulation easier.

With these and other objects in view as will appear as the description proceeds, the invention consists in the details of construction and in the arrangement and combination of parts to be hereinafter more fully set forth and claimed.

In describing the invention in detail, reference will be had to the accompanying drawings forming a part of this specification, wherein like numerals of reference denote corresponding parts in the several views, and in which:

Figure 1 is a view in elevation of the upper or first joint of a clarinet to which the invention has been applied.

Fig. 2 is a projected view of the invention *per se*,

Fig. 3 is a cross sectional view on line 3—3 of Fig. 1, and,

Fig. 4 is a fragmentary sectional view of a slight modification.

In some of the reed instruments, particularly the clarinet shown at 1 and provided with the old and well known Boehm system of keys musicians have found one note which is particularly difficult of rapid execution due to the fingering. This note is high *c* natural, position, second leger line above the staff.

In order to execute this note on the old Boehm system the player must close the thumb-hole 2 and open the octave key 3 with the thumb and all fingers of both hands must be raised from the keys. In other words the player must balance the instrument on his thumbs and steady it with his

mouth and at the same time change or adjust his embouchure every time he attacks this note.

The notes immediately above and below the high *c* and indeed the whole gamut are played with ease as these notes require the use of one or more keys and the player is thus enabled to support the instruments with his thumbs and fingers but when the high *c* note is struck the adjustment of the player's lips are disturbed as all fingers must be raised.

It is this objectionable feature which the inventor aims to avoid by the present invention. To this end, the stems 4, 5 and 6, which in the Boehm system are provided with rings for the first, second and third fingers respectively, of the left hand, are terminated short of the corresponding holes 25, 18 and 26 in the clarinet and are overridden by lugs 7 projecting from rings 8, 9 and 10. The ring 9 is provided with a shank 11 fulcrumed at 12 in the usual manner, and one end of the shank 11 overrides a pad key 13, pivoted on a pin 14 as is the practice in the art. A spring 15 tends at all times to open the key 13, but is prevented from so doing by the superior force of a stronger spring 16 tending to keep the ring 9 elevated and to press the outer end of the part 11 upon the key 13.

The key 13 covers a hole 17 relative in size to the second finger hole 18. The exact size and location of this hole 17 will be determined by experiment but it should be so located as to duplicate the note produced by the hole 18.

The rings 8 and 10 are each provided with a stem 19 and 20 respectively, pivoted in the usual manner on the pin 14. Formed integrally with the stems 19 and 20 are tappet arms 21 and 22 respectively, which overlie the key 13, but are not normally in contact therewith. When the key 13 is open and either of the rings 8 and 10 is depressed the arm 21 or 22 is brought into contact with the key 13 to close it. By this arrangement of key structure it will be seen that when the troublesome high *c* note is reached instead of lifting all the fingers as hereinbefore pointed out, the second finger will be lowered thus gripping the instrument between the thumb and second finger. The ring 9 is consequently depressed and the stem 11 releases the key 13, which under the

action of the spring 15 opens the hole 17 and the desired tone is produced the same as though the finger was off the hole 18.

In producing other notes above or below 5 high *c* the rings 8 or 10 are depressed and the arms 21 or 22 engage the key 13 to close it. Thus when a given combination of keys are actuated a given or corresponding note is produced.

10 It may here be stated that for the sake of convenience in illustration, leaf springs have been shown but if desired the usual needle springs may be used.

15 In Fig. 4 is shown a modification in which a roller 25 or other antifriction device may be interposed between moving parts and it is to be understood this structure may be used throughout the device.

20 The device may be used in connection with a six ring Boehm clarinet as well as the seven ring. In the latter construction lug 7 attached to ring 10 may be dispensed with.

25 In practical operation on the clarinet this device has proved valuable and it has been demonstrated that it is equally applicable to other reed instruments, as for instance the oboe and saxophone.

30 Although the preferred embodiment of the invention is shown, it is to be understood that slight changes may be made in the device without departing from or sacrificing any of the advantages of the invention.

35 Having thus described the invention, what I claim is:

35 1. A clarinet having a thumb hole, an octave key operable from the thumb hole, a

finger hole adjacent the thumb hole, and a third hole located to duplicate the note produced at the finger hole; and means responsive to the action of a finger at the finger hole for opening the third hole when the finger hole and the thumb hole are closed, and when the octave key is opened. 40

2. A clarinet having a thumb hole, an octave key operable from the thumb hole, a 45 pair of finger holes adjacent the thumb hole, and a normally closed third hole located to duplicate the note produced at one finger hole; means responsive to the action of a finger at one finger hole for opening the third hole when said finger hole and the thumb hole are closed and when the octave key is opened; and mechanism responsive to the action of a finger at the other finger hole for closing the third hole when the same has 50 been opened by the action of said means.

3. A clarinet having a thumb hole, an octave key operable from the thumb hole, three finger holes adjacent the thumb hole, and a normally closed hole located to duplicate the note produced at one finger hole; means responsive to the action of a finger at one finger hole for opening the normally closed hole when said finger hole and the thumb hole are closed, and when the octave 60 key is opened and independent mechanism selectively responsive to the action of fingers at the other finger holes for closing the partially closed hole when the same has been opened by the action of said means. 65
